(57) **CLAIM**

The ornamental design for a tyre cutting machine, as shown and described.

DESCRIPTION

FIG. 1 is a perspective view showing the front, top and left-side of my invention;

FIG. 2 is a perspective view showing the front, top and right-side of my invention;

FIG. 3 is an elevation view showing the left-side of my invention;

FIG. 4 is an elevation view showing the right-side of my invention;

FIG. 5 is an elevation view showing the front of my invention;

FIG. 6 is an elevation view showing the rear of my invention;

FIG. 7 is a plan view showing the top of my invention; and,

FIG. 8 is a plan view showing the bottom of my invention.
